UNITED STATES PATENT OFFICE.

WILLIAM VINCENT BUTTERFIELD, OF GREENFIELD, ENGLAND.

CORD GRIP FOR ELECTRIC FITTINGS AND APPLIANCES.

Application filed July 1, 1926, Serial No. 119,957, and in Great Britain July 14, 1925.

This invention relates to cord grips for electric fittings, such as lamp holders and electric appliances, such as irons, heaters and the like, and has for its object to provide an improved cord grip which shall be simple to construct and assemble, efficient in service, and give a secure hold upon the electric leads notwithstanding variations in thickness thereof, and by maintaining the leads apart at the place where they are gripped effectually prevent short-circuiting, due to fraying of the insulation at or adjacent the grip.

The invention comprises a head attached to or forming a part of the lamp holder or the like, said head being arranged for the admission of the leads or flexible conductors from opposite sides of a central aperture and a plug adapted for insertion between the leads to wedge or bind them securely to the said head, whilst maintaining them apart at the place where they are gripped.

Referring to the accompanying sheet of explanatory drawings:—

Figure 1 is a sectional elevation of a head and plug as aforesaid and Figure 2 a plan of the same.

Figure 3 is a sectional elevation and Figure 4 a plan showing another form of such head and plug.

The same reference letters in the different views indicate the same or similar parts.

In the example shown at Figures 1 and 2, the head *a* of vulcanized fibre or other insulating material is screwed directly into the top of a lamp holder of which a portion is indicated at *b*. The said head has a transverse slot forming lateral grooves or apertures as *c* leading into the central aperture *d*. The outer end of said central aperture *d* is threaded to receive the screw plug *e* having a tapered inner end as shown. The leads or flexible conductors indicated by letters *f* are threaded through the lateral apertures *c* and thence passed by way of the central aperture *d* to the interior of the holder *b* where, in the usual manner they are attached to the terminals or like parts, not shown. By means of the screw plug *e* the

leads are kept separate as illustrated and securely wedged or clamped to the head *a*.

In the example shown at Figures 3 and 4 the head *a* forms a part of the lamp holder itself, but in other respects it is similar to the example given by Figures 1 and 2.

What I claim is:—

1. In cord grips for electric fittings and appliances, the combination comprising an insulating head piece having a central aperture extending therethrough and a transverse slot forming lateral grooves extending from the opposite sides of the head piece to the central aperture, electricity conducting cords passing through said lateral grooves and central aperture, and a plug screwed into the outer end of the said central aperture and seating upon the said conducting cords, as set forth.

2. In cord grips for electric fittings and appliances, the combination comprising a holder, an insulating head piece in detachable connection with said holder and head piece having a central aperture extending therethrough and a transverse slot forming lateral grooves extending from the opposite sides of the head piece to the central aperture, electricity conducting cords passing through said lateral grooves and central aperture, and a plug screwed into the outer end of the said central aperture and seating upon the said conducting cords, as set forth.

3. In cord grips for electric fittings and appliances, the combination comprising a holder, an insulating head piece integral with said holder and head piece having a central aperture extending therethrough and a transverse slot forming lateral grooves extending from the opposite sides of the head piece to the central aperture, electricity conducting cords passing through said lateral grooves and central aperture, and a plug screwed into the outer end of the said central aperture and seating upon the said conducting cords, as set forth.

In testimony whereof I have signed my name to this specification.

WILLIAM VINCENT BUTTERFIELD.
